UNITED STATES PATENT OFFICE.

WILLIAM S. HUTCHINSON, OF BETHLEHEM, PENNSYLVANIA.

FLOOR CONSTRUCTION.

1,354,560.

Specification of Letters Patent.

Patented Oct. 5, 1920.

Application filed May 15, 1919. Serial No. 297,211.

To all whom it may concern:

Be it known that I, WILLIAM S. HUTCHINSON, a citizen of the United States, and a resident of Bethlehem, in the county of 5 Northampton and State of Pennsylvania, have made a new and useful Invention in Floor Construction, of which the following is a specification.

My invention relates to building construction and particularly to that type of building wherein steel floor beams of girder construction are spaced in parallel rows and subfloors of reinforced concrete are applied thereto. To avoid the costly process of 10 erecting numerous forms for pouring the concrete in its final position, it is the growing practice to form the subfloor of slabs of reinforced concrete manufactured in suitable widths and lengths at a convenient 15 point and shipped to the locations of the buildings being erected.

The usual method of applying these pre-cast slabs is to support them upon the top 20 of the floor beams with adjacent slabs practically abutting each other. To secure strength, the slabs are of modified arch construction, being from four to six inches in 25 depth. This depth of slab when used in above construction results in the addition of 30 such dimension to the distance between each ceiling and the floor above which, in a multi-storyed building, becomes a considerable factor in the amount of steel, brick, plumbing, labor and other costs necessary to erect 35 the building.

The object of my invention is to decrease this additional thickness at each floor. In my patent application, Serial Number 40 297,210, I disclose certain methods of applying the subfloor below the tops of the floor beams by resting the slabs on the lower flanges of the beams. My present invention discloses another method of accomplishing 45 this result and is illustrated in the accompanying drawings forming part of this specification and in which Figure 1 is a plan of a portion of a subfloor of my improved construction, Fig. 2 is a vertical transverse section through a floor slab and its supporting beams when the beam is fireproofed beneath the floor slabs and Fig. 3 is a section 50 through one floor beam only where such fireproofing is omitted.

The floor beams 1 may be of I beams as 55 shown or any other type, either integral or

built up, having upper and lower flanges 2 and 3 respectively. At intervals along the beam, I apply an inverted U shaped hanger or yoke 4 having a horizontal portion 5 and depending sides 6. Portion 5 rests upon the 60 top flange 2 of the floor beam and may be secured thereto. When fireproofing is applied to the bottom flange 3 of beam 1, sides 6 of the yoke extend downwardly and support the fireproof slabs 7 by means of bolts 8 which are flattened at one end to be secured to side 6 of yoke 4 and are provided with a nut 9 to hold the slab 7. Any other suitable slab retaining means may be substituted for bolt 8 and nut 9. 70

Below the top of beam 1 and running parallel therewith are continuous, floor slab support angles 10. The vertical flange of each angle is secured to the outside of successive sides 6—6 of hangers 1—1 and its 75 horizontal flange is faced away from the beam. The horizontal flanges of opposed angles 10—10 respectively support the opposite edges of each floor slab 11.

Clips 12 act as bracing members to prevent 80 opposed supporting angles 10 from spreading away from each other and may be applied to the inside of hangers 4 as shown or directly to the back of angles 10 at other intervals. If hangers 4 are sufficiently heavy to resist any bending force 85 likely to be imposed on them or are adequately braced by bottom flanges 3 and slabs 7, bracing clips 12 may be omitted.

My construction makes it possible to utilize 90 the pre-cast floor slabs with all their desirable features without increasing the height of each story and without removing any portion of the floor beam to insert it in place. It is very easy to lower the slabs 95 into place as there is no framing extending above the slab outline to be removed or dodged in placing the slabs between the top and bottom flanges of the floor beams.

I claim:—

1. In a floor structure, a floor beam, yokes spaced along the beam and mounted thereon, a floor support member extending parallel to said beam and secured to said yokes; a yoke reinforcing member, secured to each yoke near the point of support of said support member and located between the yoke and the beam and engaging the web of the beam, and floor units having edges mounted on said floor support member. 105 110

2. In a floor structure, parallel floor beams, yokes spaced along the beams and straddling the top flange thereof, a separate floor supporting member secured to the 5 yokes associated with each beam and extending longitudinally of the beam, and a separately formed floor unit located between said beams and having its edges supported by said floor supporting members.
- 10 3. In combination in a floor structure, parallel floor beams, yokes spaced along each floor beam and straddling the top cord thereof, a separate continuous floor support member extending longitudinally of each 15 beam and rigidly secured to the yokes associated with the beam, and separately formed floor slabs located between said

beams and supported at their edges only by said floor support members.

4. In a floor structure, a floor beam, yokes spaced along the beam and mounted thereon, a floor support member extending parallel to said beam and secured to said yokes, a yoke support member, secured to each yoke at the point of support of said floor support member and located between the yoke and the beam and engaging the web of the beam, and floor units having their edges mounted on said floor support member.

In testimony whereof I have hereunto 30 subscribed my hand this 6th day of May, 1919.

WILLIAM S. HUTCHINSON.
